UNITED STATES PATENT OFFICE.

CHARLES J. HARKINS, OF BUFFALO, NEW YORK.

GAGE-COCK.

No. 851,235.

Specification of Letters Patent.

Patented April 23, 1907.

Application filed December 26, 1906. Serial No. 349,368.

To all whom it may concern:

Be it known that I, CHARLES J. HARKINS, a citizen of the United States, residing at Buffalo, in the county of Erie and State of New York, have invented a new and useful Improvement in Gage-Cocks, of which the following is a specification.

This invention relates to gage cocks which are used on boilers for testing them as to the level of the water in the same.

Heretofore gage cocks have usually been so constructed that when they became leaky the boiler had to be shut down in order to permit of either repairing or replacing the gage cock which often was attended with considerable inconvenience and loss of time particularly when it occurred on the boiler of a locomotive in active service and necessitated interruption of the work in which the locomotive was engaged.

The object of this invention is to provide a gage cock in which a leak may be stopped without necessitating shutting down of the boiler and which can be interchanged to permit repair or replacement of the worn parts to be deferred until such a time as will be more convenient.

In the accompanying drawings: Figure 1 is a longitudinal section of one form of my improved gage cock. Figs. 2 and 3 are cross sections thereof in the correspondingly numbered lines in Fig. 1. Fig. 4 is a detached sectional view of a modified construction of the reversible rear casing section of my improved gage cock and the parts connected therewith.

Similar letters of reference indicate corresponding parts throughout the several views.

The gage cock shown in Figs. 1—3 and embodying my invention has a tubular or hollow body or casing composed essentially of a front section A, a rear section B and a bonnet C. The front section may be provided at its front end with an external screw thread a, as shown or with other means for securing the same in an opening of the boiler. The rear section B is reversible and may be connected at opposite ends with the opposing ends of the front section and the bonnet by means which permit of readily detaching these parts from each other. The means for this purpose shown in the drawings, as an example, consists in providing opposite ends of the rear section with external screw threads which engage with internally threaded sockets a', b'

formed, respectively, at the rear end of the front body section and the front end of the bonnet. The front section of the body is provided centrally with a main longitudinal bore d of comparatively small diameter and at its front end with a bore D of larger diameter forming a valve chamber. A valve seat e is formed on this section at the junction of its front and central bores which tapers rearwardly.

F represents a check valve arranged in the chamber D of the front body section and having a rearwardly tapering face which is adapted to engage with the valve seat of said body section. This valve is provided with rearwardly-projecting stem f of angular or flat-sided cross section which is arranged in the main bore of the front body section and terminates at its outer or rear end short of the outer end of said main bore. The check valve may be prevented from escaping from the valve chamber D by any suitable means but preferably by a cross pin g secured to the front body section in front of the check valve, as shown in Fig. 1.

The outer end of the bonnet is provided with an internally screw threaded opening which receives a valve shifting spindle H having an external screw thread which works in said opening of the bonnet and a handle, wheel or knob h at its rear end whereby the same may be turned. The rear end of this valve spindle is provided with an axial opening or socket i.

The central portion of the rear body section is provided with a lateral outlet in which a discharge nozzle J is secured and at opposite ends of this section the same is provided with heads K, K having axial openings or ports k, k whereby the interior or main valve chamber L of this section is connected respectively with the interior of the front body section and the bonnet. At the inner ends of the port openings k, k the rear body section is provided with valve seats l, l which preferably are of conical form and taper outwardly in opposite directions from the interior of this section.

M represents the enlarged central part of a reversible valve stem and m, m its two reduced shanks arranged at opposite ends of the central part. The central part M of this stem is arranged within the main valve chamber, its front shank m projects through the front port k into engagement with the rear end of the stem of the check valve and

the rear shank projects from the central part M rearwardly through the rear port k into the socket of the shifting spindle. At the junction of the enlarged central part of the 5 reversible valve stem and its reduced shanks, the same is provided with two main valves n, n preferably of conical form and tapering in opposite directions and adapted to co-operate respectively, with the valve seats at opposite ends of the front body section. Adjacent to each of the main valves the shanks are made of flat-sided cross section, as shown at n¹, or of other form to permit the passage of steam or water through the openings containing those portions of the shanks, and the extreme ends of these shanks may either be made round, as shown at n², or of any other desired form. To permit of introducing the reversible valves into the main valve chamber, 20 the heads bearing the seats k, k may both be made in the form of plugs which are removably placed into opposite ends of the main chamber and held in place by external annular flanges o, o thereon clamped between 25 opposite ends of the rear body section and the adjacent ends of the front section, and bonnet, as shown in Fig. 1.

If desired, the main valve chamber may have one of its heads made integral with said 30 body section as shown at K¹ in Fig. 4, while the other is made removable therefrom and held in place in the manner above described.

While in use the gage cock is closed or shut off by turning the spindle forwardly for causing 35 the same to move forwardly in the bonnet during which movement the bottom of the spindle socket engages with the rear end of the reversible valve stem and shifts the front or active main valve n into engagement with the front seat l of the front body section for shutting off the escape of steam or water and at the same time the front end of the reversible valve stem engages with the 40 rear end of the check valve stem and moves the check valve away from its seat.

When it is desired to test or try the boiler the spindle is turned backwardly sufficient to permit the steam or water pressure against the check valve and front main valve to 45 move the latter from its seat but not sufficient to permit the check valve to engage its seat, thereby enabling the steam or water of the boiler to pass through the front and rear body sections and escape through the nozzle. After testing the boiler in this manner the 55 front main valve is again moved toward its seat to prevent the further escape of steam or water.

If the front main valve or its seat becomes 60 worn and permit leakage the spindle is turned backwardly beyond what is necessary for testing until the reversible valve stem has been withdrawn sufficient to permit the check valve to bear against its seat. The 65 escape of steam and water from the boiler is

now prevented by the check valve. The rear body section may now be detached at its opposite ends from the bonnet and front body section together with the reversible valve stem and after being turned end for end the rear body section may be connected in the reversed position with the bonnet and front body section, the opposite ends of its reversible valve stem also exchanging engagement with the check valve stem and the shifting spindle, respectively. In this reversed position of the rear body section and the valve stem, the main valve and its seat which were previously inactive now become the active means for controlling the escape 80 of steam or water from the boiler during the testing operation, the opening and closing of this valve being effected in the same manner as previously described.

When both of the main valves become 85 leaky or worn, the rear body section and the reversible valve stem and its valve seats may be entirely renewed, the check valve holding the steam and water from escaping while this renewal is being effected. When both heads 90 of the rear body section are made separate from this section only its heads need be renewed when the main valve seats become worn out but when the main valve seat of the integral head on the front body section becomes worn it is necessary to renew the front body section also.

Ordinarily the screw joint between the front and rear body sections and the spindle is sufficiently tight to prevent the escape of any steam or water through the same from the rear end of the body section. In order however to positively prevent any steam or water from passing from the rear body section through its rear end into the bonnet a circular packing, ring or washer P is placed between the rear end of the enlarged central part of the reversible valve stem and the rear part of the bore of the main valve chamber, as shown in Fig. 1, thereby obstructing the 100 passage of steam or water at this point. Upon reversing the front body section and the double valve stem this packing is pushed toward the opposite end of the reversible valve chamber and stem so as to prevent the 105 escape of steam and water into the bonnet in this changed position of the parts.

It will be noted that a gage cock constructed in accordance with my invention furnishes ample reserve facilities which may be instantly called into service for stopping leakage of the gage cock and enables more extensive repairs of the same to be deferred until a more opportune time arrives, thereby avoiding expensive and annoying delays 115 which frequently occur by the use of gage cocks as now commonly constructed.

I claim as my invention:

1. A gage cock comprising a casing having a front section provided with a valve seat 120

- and a reversible rear section provided centrally with an outlet and at opposite ends with valve seats and adapted to be detachably connected at either of its ends with the rear end of said front section, a check valve arranged in said front section and adapted to close against the seat thereof, a pair of connected main valves arranged in said rear section and co-operating respectively with the seats thereof and also with said check valve, and means for operating said valves, substantially as set forth.
2. A gage cock comprising a casing having a front section provided with a valve seat and a reversible rear section having an outlet and adapted to be detachably connected at either end with the rear end of said front section, heads arranged at opposite ends of said rear section and each provided with a port and a valve seat around the port, a check valve arranged in the front section and adapted to engage with the seat thereof, a valve stem extending through said front section and into engagement at its front end with the check valve and having a pair of valves which are adapted to engage the seats of said rear section, and means for operating said valves, substantially as set forth.
3. A gage cock comprising a casing having a front section provided with a valve seat and a reversible rear section having an outlet and adapted to be detachably connected at either end with the rear end of said front section, heads arranged at opposite ends of said rear section and each provided with a port and a valve seat around the port, a check valve arranged in the front section and adapted to engage with the seat thereof, a valve stem extending through said front section and into engagement at its front end with the check valve and having a pair of valves which are adapted to engage the seats of said rear section, a bonnet adapted to be detachably connected with the rear end of said rear section, and a screw threaded shifting spindle working in said bonnet and operatively engaging the rear end of said reversible valve stem, substantially as set forth.
4. A gage cock comprising a casing having a front section provided with a valve seat and a reversible rear section provided with an outlet and adapted to be connected at either end with the rear end of said front section, heads arranged at opposite ends of said front section each provided with a port and a seat, one of said heads being formed integrally with said rear section while the other is separable therefrom, a check valve arranged in said front section and adapted to engage the seat thereof, and a reversible valve stem extending through said rear section with its front end in engagement with said check valve and having a pair of main valves adapted to co-operate respectively with the seat of said rear section, and operating means engaging with the rear end of said reversible valve stem, substantially as set forth.
5. A gage cock comprising a casing having a front section provided with a valve seat and a reversible front section provided with an outlet and adapted to be connected at either end with the rear end of said front section, heads arranged at opposite ends of said front section each provided with a port and a seat, one of said heads being formed integrally with said rear section while the other is separable therefrom, a check valve arranged in said front section and adapted to engage the seat thereof, and a reversible valve stem extending through said rear section with its front end in engagement with said check valve and having a pair of main valves adapted to co-operate respectively with the seat of said rear section, a bonnet detachably connected with the rear end of said front section, and a screw threaded shifting spindle working in said bonnet and engaging with the rear end of said reversible valve stem, substantially as set forth.
6. A gage cock comprising a casing having a front section provided with a valve seat and a reversible rear section having an outlet and adapted to be detachably connected at either end with the rear end of said front section, heads arranged at opposite ends of said rear section and each provided with a port and a valve seat around the port, a check valve arranged in the front section and adapted to engage with the seat thereof, a valve stem extending through said front section and into engagement at its front end with the check valve and having a pair of valves which are adapted to engage the seats of said rear section, a bonnet adapted to be detachably connected with the rear end of said rear section, and a screw threaded shifting spindle working in said bonnet and operatively engaging the rear end of said reversible valve stem, substantially as set forth.
